SAFETY RAZOR

Isaiah N. Zeller, New York, N. Y., assignor to
 American Safety Razor Corporation, Brooklyn,
 N. Y., a corporation of Virginia

Original application November 3, 1920, Serial No.
 421,466. Divided and this application August
 16, 1926, Serial No. 129,359

10 Claims. (Cl. 30—12)

This invention relates to safety razors but more particularly to blade holders for the same and has for its primary object to provide a structure which is simple, durable and efficient.

5 Another important object is to provide a form of blade holder which will permit the use of a double edged blade as well as single edged blades in types of safety razor frames now capable of using only a single edged blade.

10 Further objects of the invention are to save materials, to facilitate cleaning, and to provide a separate blade holder.

15 The many other objects and advantages of the present invention will be better understood by reference to the following specification in connection with the accompanying drawing disclosing certain selected embodiments thereof in which:

Fig. 1 is a front elevation of one embodiment 20 of my invention.

Fig. 2 is the same as Fig. 1 with the holder mounted in a safety razor guard, a portion of the cover being removed; and

25 Fig. 3 is a section on the line 3—3 of Fig. 2. Single edge blades now in general use either have a thickened rear edge to provide the necessary rigidity or, in the case of the sheet steel blade, a rigid head is pressed over the rear edge and permanently attached thereto. The thickened blade requires the use of considerable steel and is expensive to produce so that the sheet metal blade has largely superseded it. When the single sharpened edge becomes dull, the blade must be resharpened or the blade and head discarded as they are not separable. With the blade holder of the present invention the proper reinforcing is procured and the same holder may be used with an indefinite number of blades of either the single or double edge type.

40 Referring to the drawing, the embodiment of the invention of Figs. 1, 2, and 3 are shown to comprise a base plate 33 provided with inturned end portions 34 on opposite ends thereof forming a channel or channels to receive and overlap the end edges of a blade 35. The lower portion of these end portions are spaced sufficiently from the body of the base plate to permit the blade 35 to be slid upwardly therebetween to the desired position. The end edges of the blade 50 are beveled from the center and the end portions 34 are bent angularly to fit these beveled edges. The angularity of the end portions 34 and the dimension of the parts are such as to prevent the blade advancing too far into the holder.

55 Where a double edged blade is employed, that

is, a blade which has its oppositely disposed edges sharpened, as shown in the drawing, I may, in order to enable the user to distinguish between these edges and thus permit him to hold one edge in reserve until the other edge has become dull, place identification marks on each sharp edge such as numerals 1 and 2.

The base plate is here shown by me as extending beyond the rear edge of the blade when the blade is fully inserted into the channel or 10 channels as result of which I attain the result that in connection with the use of a double edged blade, the rear edge of the blade is protected and in connection with the use of either single or double edged blades, I am enabled to use a 15 blade as much shorter than the holder, as may be found advisable or necessary, and am thus enabled to employ a blade, the depth of which is materially shorter than if used without the base plate.

20 While my invention may be employed with that type of razor in which the blade is dropped loosely into place on the guard and some means has been provided to press against the rear edge of the blade to force the forward sharpened edge against stops provided on the frame, I have illustrated my invention as used in the form of safety razor illustrated in Figs. 2 and 3 of the drawing in which I have shown the holder as connected permanently to the frame. The 25 form of connecting means would naturally vary with the construction of the frame or might be varied in any particular type of frame and in the type of frame shown in Figs. 2 and 3 of the drawing, I have provided the base plate 33 with 30 slots 36 to receive strips 37 of metal which have their lower portions bent into a loop 38 and their upper extremities folded about the spring arms 39 in the frame as shown in Figs. 2 and 3. These 35 spring arms 39 form the holder support which 40 yieldingly presses the blade against the usual stops 40 on the frame. Lifting of the cover 41 draws the blade away from the stops 40 and exposes the guard teeth 32 in the manner described in connection with the previous embodiment. In this construction also it will be noted that the pressure usually exerted against the rear 45 edge of the blade is taken by the holder.

From the foregoing description, it will be understood that the present invention provides a 50 cutting unit for safety razors and that this cutting unit is made up of a razor blade which may be double edged and a holder therefor, these two parts of the cutting unit being so associated that they may be placed as a unit in or upon different 55

types of safety razor frames which are originally constructed for using single edged blades only.

It will therefore be seen that my improved blade holder is simple in construction, durable and efficient. It permits the use of double edged blades as well as single edged blades in safety razors now only capable of using a single edge blade. The holder is readily separable from the blade so that one holder may be used with an indefinite number of blades and will provide the proper protection and reinforcement. The holder makes possible a considerable saving in materials because the base plate will strengthen the entire blade, and enable an exceedingly narrow blade to be used. This holder is capable of use unattached to the safety razor or it may be attached thereto permanently. The attaching of the holder to the frame greatly facilitates the cleaning of the frame and the blade. The marking of the edges of a double edge blade makes it possible for the user to continue to use one edge until this has become dull and then to use the other edge.

I am aware that many changes in construction and in arrangement of parts may be made without departing from the invention and I reserve the right to make all such changes as fairly fall within the scope of the following claims.

Having thus described my invention and illustrated its use, what I claim as new and desire to secure by Letters Patent, is

1. A cutting unit for safety razors comprising a double edged razor blade and a holder therefor, said holder having tapering channels receiving the ends of the blade and extending in a direction from front towards the rear of the holder and limited in its insertion to a position with its active edge projecting forwardly beyond the front edge of the holder and its rear edge between its end portions short of the rear edge of the holder and protected thereby.

2. A cutting unit for safety razors, comprising a double edged razor blade and a holder therefor, said holder having a tapered channel receiving the ends of the blade and extending in a direction from front to rear of the holder, the blade being inserted from the front towards the rear of the holder, and adapted to limit the insertion of the blade to a position with its active edge projecting forwardly beyond the front edge of the holder and its rear edge between its end portions short of the rear edge of the holder and protected thereby.

3. In combination with a wafer-type blade having a front shaving edge and side edges beveled at their rear ends, a razor comprising a blade seat having a guard, blade stops associated with the guard to limit the advancement of the shaving edge thereover, and means engaging said beveled rear ends for advancing said shaving edge against the front stops.

4. In combination with a wafer-type blade having a front shaving edge and side edges beveled at their rear ends, a razor comprising a blade seat having a guard, blade stops associated with the guard to limit the advancement of the shaving edge thereover, and means including tapered blade guides for engaging said beveled rear ends of the blade to advance the shaving edge against said stops.

5. In combination with a double-edged wafer-type blade having side edges beveled so as to converge toward each shaving edge, a razor comprising a blade seat having a guard, blade stops associated with the guard to limit the advancement of a selected shaving edge thereover, and means engaging the beveled side edges adjacent to the inoperative shaving edge for advancing the selected shaving edge against said stops, said means including tapered guides adapted to engage about said beveled side edges.

6. In combination with a wafer-type blade having a front shaving edge and side edges each of which includes at least two points arranged along a line oblique to the shaving edge, a razor comprising a blade seat having a guard, blade stops associated with the guard to limit the advancement of the shaving edge thereover, and means engaging said side edges at said two points for advancing said shaving edge.

7. In combination, a razor comprising a blade seat, a guard on said seat, blade stops associated with said guard and defining a proper predetermined positional relationship between the shaving edge of a blade and the guard, and blade-advancing means including tapered blade guides, and a wafer-type blade adapted to be advanced along said seat and against said blade stops, whereby the shaving edge of the blade is properly located with respect to the guard along a line of maximum shaving efficiency, said blade having beveled side edge engageable by said guides.

8. In combination, a razor comprising a blade seat, a guard on said seat, blade stops associated with said guard, and blade-advancing means including tapered blade guides, and a double-edged wafer-type blade adapted to be advanced along said seat and against said blade stops so as to properly position a selected cutting edge over said guard, said blade having its sides beveled so as to converge toward each shaving edge, and the sides adjacent to the inoperative shaving edge being engageable by said guides.

9. In combination, a razor comprising a blade seat, a guard on said seat, blade stops associated with said guard, and blade-advancing means including tapered blade guides, and a double-edged wafer-type blade adapted to be advanced along said seat and against said blade stops so as to properly position a selected edge over said guard edge, said blade having its sides beveled so as to converge toward each edge, and the sides adjacent to the inoperative edge being engageable by said guides; and said blade being symmetrical about an axis parallel to its edges whereby it may be reversed.

10. In combination with a wafer type razor blade having beveled side edges which converge rearwardly, a blade holder including a blade seat having a guard edge, blade stops associated with the guard edge to limit the advancement of a front blade edge relative to said guard edge and means associated with the blade holder for advancing the blade through engagement with its beveled side edges to bring its shaving edge into engagement with the front stops whereby the blade is wedged forwardly against the front stops by engagement of its converging side walls.

ISAIAH N. ZELLER.
